Attorney

UNITED STATES PATENT OFFICE.

CHARLES KOHL, OF SHEBOYGAN, WISCONSIN.

BROODER.

1,303,804.

Specification of Letters Patent. Patented May 13, 1919.

Application filed April 23, 1918. Serial No. 230,341.

To all whom it may concern:

Be it known that I, CHARLES KOHL, a citizen of the United States, residing at Sheboygan, in the county of Sheboygan and 5 State of Wisconsin, have invented certain new and useful Improvements in Brooders, of which the following is a specification.

This invention relates to improvements in brooders and it is the principal object of the 10 invention to provide an improved heating and ventilating means for brooders whereby the several compartments thereof can be maintained at the proper temperatures and as a consequence, insure proper husbanding 15 of the chicks therein.

Another and equally important object of the invention is to provide the brooder with means for utilizing the waste products of combustion for heating the flooring of the 20 brooding chamber, thus, effecting a material saving of fuel and lending to the efficiency of the construction.

Another important characteristic of the invention resides in the provision of a novel 25 form of ventilator which is arranged in a manner such as will allow the same to communicate with either the brooding or scratching chambers of the brooder, as desired.

30 Other objects will be in part obvious and in part pointed out hereinafter.

In order that the invention and the manner of its application may be readily understood by those skilled in the art, I have in 35 the accompanying illustrative drawings and in the detailed following description based thereon set forth a preferred embodiment of the invention.

In the drawings:

40 Figure 1 is a vertical longitudinal section through the improved brooder,

Fig. 2 is a fragmentary horizontal section therethrough, and

45 Fig. 3 is a fragmentary detail in section of the novel ventilator.

Having more particular reference to the drawings, in connection with which like reference characters will designate corresponding parts throughout the several views, 1 50 represents the housing of the brooder in its entirety, the same having the upper portion thereof inclined and partly covered by a suitable roofing, while a sash 2 is hinged to the upper portion of the same adjacent the 55 opening in one side of the roofing as at 3 and

obviously is adapted to close the same and yet admit sufficient light to the brooder. A removable closure 4 is arranged over the opening in the remaining upper side of the housing and is so constructed as to afford 60 an airtight jointure between the same.

A flooring 5 is arranged in the bottom of the housing 1 and as will be noted, has extending across the intermediate portion thereof an inclined runway 6, the said runway 65 communicating with the brooding and scratching chambers 7 and 8 of the brooder.

As will be noted, the brooding chamber 7 is provided with a double walled flooring 9 having openings 10 formed therein and 70 ways formed by diagonally extending parallel strips 11 communicating with said openings, which strips as will be noted, are arranged between the several walls of said flooring 9 and serve as means for conducting 75 heat to all portions of the same, thereby insuring proper heating. Vent openings 12 are formed in the sides of the housing 1 at points adjacent the flooring 9 and as will be readily understood, serve as means for promoting the circulation of the heated air 80 between the several walls thereof.

Arranged upon the flooring 9 directly over the openings 10 is a tank 13 provided with a suitable filling opening 14 whereby 85 water or other suitable fluid may be arranged therein; the lower portion or bottom of the tank being formed conical as at 15 to afford a greater heated area and for also causing the waste products of combustion to be deflected therefrom into the space occurring 90 between the double walls of the flooring 9.

Extending through a portion of the roofing of the brooder is a ventilating pipe 16, the upper end thereof having a cowl 17 adjustably arranged therein, while the lower end is flanged as at 18 in order that an angularly disposed secondary vent pipe 19 can be rotatably secured thereto, said pipe being also provided with an annular flange upon 100 its adjacent end which as will be noted, is received over the flanged portion 18. By so mounting the ventilating pipe 19, communication between the same and either of the chambers 7 or 8 of the brooder may be established at will by a user.

To divide the brooding chamber 7 and the scratching chamber 8, I preferably hang from the top of the housing a heavy fabric curtain 20, the lower marginal portion there- 110

of being arranged in spaced relation to the flooring 9.

Positioned in the space occurring between the flooring 5 and 9 is a heating lamp 21, the same of course being placed therein by way of a suitable opening formed in one portion of the housing and provided with a door, not shown.

From the foregoing it will be understood by those skilled in the art that I have provided an exceedingly simple and efficient brooder construction; the same by reason of the plurality of compartments affording a brooding chamber and a scratching chamber for the chicks therein. Since the flooring 9 is spaced from the main flooring 5, the same when heated by the waste products of combustion circulating therebeneath will afford sufficient warmth for the chickens and efficiently husband the same. Further, when the heating lamp 21 is lighted the tank 13 and the water therein will be heated, and thus radiate sufficient heat to maintain the chambers in the brooder at proper temperatures; it being understood that the waste products of combustion from the heating lamp are directed by way of the strips 11 into the space occurring between the several walls of the flooring 9. The scratching chamber of the brooder of course will be maintained at a temperature lower than the temperature of the brooding chamber 7, this being rendered possible due to the provision of the curtain 20 and the arrangement of the secondary ventilating pipe 19. By turning the pipe 19 to communicate with the brood-

ing chamber 7, the same will of course then act to ventilate the same, while should the pipe 19 be turned to communicate with the chamber 8, a suitable opening 20' being formed in the curtain 20, it will then serve to ventilate this particular chamber. By adjusting the cowl 17 with relation to the upper end of the ventilating pipe 16, the draft therethrough may be controlled to the desired extent.

Manifestly, the construction shown is capable of considerable modification and such modification as is within the scope of my claim, I consider within the spirit of my invention.

I claim:

In a brooder, a plurality of chambers therein, one of said chambers having a secondary double walled flooring therein supported in spaced relation to the main flooring of the same, parallel strips arranged between the walls of said secondary flooring to provide ways therein, said ways communicating with vent openings formed in adjacent portions of the brooder, portions of the secondary flooring having openings formed therein, heating means positioned below the flooring adjacent said openings, a fluid containing tank arranged on the secondary flooring above said openings, and ventilating means intermediate the end walls of the brooder capable of directly communicating with either of said chambers.

In testimony whereof I affix my signature hereto.

CHARLES KOHL.
